UNITED STATES PATENT OFFICE.

DAVID S. THOMAS, OF BROOKLINE, MASSACHUSETTS, ASSIGNOR TO JASON WEILER,
WILLIAM WEILER, AND GUSTAVUS WEILER, DOING BUSINESS UNDER THE FIRM
NAME OF JASON WEILER & SONS, OF BOSTON, MASSACHUSETTS.

FINGER RING.

Application filed March 11, 1924. Serial No. 698,363.

To all whom it may concern:

Be it known that I, DAVID S. THOMAS, a citizen of the United States, residing at Brookline, in the county of Norfolk and 5 State of Massachusetts, have invented new and useful Improvements in Finger Rings, of which the following is a specification.

The chief object of this invention is to provide a pair of finger rings, one of which 10 may be called a primary ring, and is adapted for use by itself as an engagement ring, while the other may be called a secondary ring, and is adapted for subsequent use, with the primary ring, as a wedding ring, 15 the rings having the same internal diameter and each ring being provided with coupling means, so that the rings may be interlocked and are inseparable when in use.

Another object is to so improve the construction of the primary ring that it is provided with coupling means wholly within its body, so that the external form of the ring is not changed by the coupling means, there being no external projection caused 25 by said means, rendering the use of the primary ring by itself, as an engagement ring, undesirable.

I attain the above-mentioned and other related objects by the improved construction 30 hereinafter described and claimed.

Of the accompanying drawings forming a part of this specification,—

Figure 1 is a side view, on an enlarged scale, of the primary ring.

Figure 2 is a section on line 2—2 of Figure 1.

Figure 3 is a side view, and

Figure 4 an edge view of the secondary ring.

Figure 5 is a sectional view, showing the relative positions of the two rings when the coupling means of the secondary ring is first inserted in the coupling means of the primary ring.

Figure 6 is a sectional view, showing the coupling means of the two rings interlocked.

Figure 7 is a view similar to Figure 2, showing a different construction of the primary ring.

The same reference characters indicate the same parts in all of the figures.

The primary ring 12 may have any desired external form and ornamentation, such as may be required by custom and con-

vention in an engagement ring, the ring 55 having annular oppositely facing edge portions 12^a and 12^b, surrounding the finger-receiving opening, and a cavity between said edge portions at one side of said opening. An essential element of this ring is a coupling means wholly within the body of the ring, said means including the annular edge portion 12^a and a key-hole 13, in said edge portion, preferably formed as shown by Figure 1, one end of the keyhole being enlarged.

The secondary ring 14 may also have any desired external form and ornamentation, such as may be required by custom or convention in a wedding ring. An essential 70 element of this ring is a coupling means wholly external to the body of the ring and embodied in a key including a shank 15, fixed to, and projecting from one of the annular edge portions of the ring, and a head 16, enlarged at one end as shown by Figure 3, and formed to pass through the key-hole 13.

The arrangement is such that the key is 80 insertible in the key-hole only when the ring 14 is out of coincidence with the ring 12, as shown by Figure 5. When the key is inserted and the ring 14 is turned into coincidence with the ring 12, as shown by Figure 6, the head 16 of the key engages 85 the edge portion 12^a at one end of the key-hole, so that the rings are inseparable when placed on a finger.

The shank 15 of the key fits closely, and is adapted to turn in the enlarged end of the 90 key-hole 13, but is prevented from moving sidewise therein.

It will now be seen that the ring 12 is adapted to be used by itself as an engagement ring, there being no coupling means 95 projecting from its external surface to render such use undesirable. The key-hole 13 is so small in a ring of operative size, that it is inconspicuous and not noticeable.

The construction is such that the internal 100 diameter of each ring may be exactly the same as that of the other, so that when the period of use of the ring 12 by itself has expired, the two rings may be interlocked and worn as one.

The cavity in the ring 12, formed in part by the edge portion 12^a, may be an open cavity 17, communicating with the interior

of the ring, as shown by Figures 2, 5 and 6, particularly when the ring is made of expensive material such as platinum. If desired a closed cavity 17^a may be provided, 5 as shown by Figure 7, the ring having an inner wall entirely surrounding the finger opening.

It is at present customary to ornament 10 the portion of a wedding ring which is exposed at the outer side of the finger, by gems set in the outer portion of the ring. It is obviously unnecessary to thus ornament the inner portion of the ring. It will be seen 15 that the secondary ring 14 may be provided with gems only at its outer side portion, this being the portion from one edge of which the key projects, and that when the rings are interlocked, the secondary ring is prevented 20 from turning on the finger independently, so that its gems may be confined in a predetermined relation to a gem or gems set in the outer portion of the primary ring.

I claim:

25 1. A finger ring having annular oppositely facing edge portions surrounding the finger-receiving opening, a cavity between said edge portions at one side of said opening, and a key-hole formed in one of said 30 edge portions and communicating with said cavity, the said edge portion and key-hole being adapted to engage a key projecting from an annular edge portion of a secondary ring.

35 2. A pair of finger rings including a pri-

mary ring having coupling means wholly within its body, and embodied in an edge portion forming a wall of an internal cavity, and provided with a keyhole; and a secondary ring having coupling means 40 wholly outside its outer surface, and embodied in a key projecting from an edge face of the secondary ring and adapted to be inserted in said key-hole and engage the edge portion of the primary ring in which the key-hole is formed, the arrangement being such that the key is insertible in the key-hole only when the auxiliary ring is out of coincidence with the primary ring, and is interengaged with said edge portion 50 when the two rings coincide.

3. In combination, a primary ring having a cavity between its opposite edge portions, one of said edge portions having a key-hole communicating with said cavity; 55 and a secondary ring having a key fixed to, and projecting laterally from one of its edge portions, and adapted to enter and turn in said key-hole, the finger-receiving openings of the two rings being substantially the 60 same diameter, the arrangement being such that the key can enter and leave the key-hole only when the rings are out of coincidence with each other, and is interlocked with the edge portion containing the key-hole when the rings coincide with each other.

In testimony whereof I have affixed my signature.

DAVID S. THOMAS.
